WRIST WATCH STRAP

Samuel Friedman, Cedarhurst, N. Y., assignor to
 Brite Specialty Company, New York, N. Y., a
 firm composed of Samuel Friedman and Meyer
 Friedman

Application September 24, 1943, Serial No. 503,605

3 Claims. (Cl. 224—4)

1

This invention relates to an improved wrist watch strap.

Wrist watch straps are made up to comprise two sections, namely, a tongue section and a buckle holding section. The tongue section is provided at one end with a watch attaching portion; and the buckle holding section is provided at one end with a similar watch attaching portion and at the other end with a buckle attaching portion. Each watch attaching portion is made by forming a loop in the strap material at the affected watch strap end, which is referred to as the watch attaching loop.

Wrist watch casings are constructed with so-called end bars or bails to which the watch strap loops attach. With certain types of watches, particularly those of large size, the bars, provided with spring controlled pins are removable; and consequently little trouble is experienced in fitting these into the watch strap loops and snapping the bars, with the strap sections attached, onto the watch casing. For such cases the watch strap loops may be made by simply looping or folding under the bottom strap portion and stitching the same at the sides to the upper strap portion, leaving the loop unstitched and open. With other types of watches, however, such as watches of small size, the bars are not removable but are fixed to the watch casing. For such cases, the loop cannot be permanently stitched but an open tongue must be provided which can be threaded through the space between the bar and the casing proper. Here considerable difficulty arises in permanently securing the open tongue in position after its attachment to the watch bar.

The prior art has attempted, but only with indifferent success, to solve this problem by associating the open tongues with metal elements such as bar holders and locking prongs. These increase manufacturing costs and troubles and are not too acceptable in use. It has also been attempted to thread long tongues through a number of slots in the strap, but these offer insecure and ungainly answers to the problem.

The prime object of my present invention centers about the provision of a watch strap which offers a fully effective solution to this problem because it possesses all the characteristics desired for the purpose; these are:

1. The watch strap is devoid of metallic attachments; it is made wholly of the material from which the strap is fashioned, such as leather or a plastic;

2. The open tongue may be readily attached to

2

the watch by the user or watch dealer; the tongue is easily threadable as by means of any convenient or available metal draw element (for example, a clip) through the watch and strap parts;

3. The tongue locks in position, and securely, as soon as it is attached; and

4. The construction is attractive and simple.

To the accomplishment of the foregoing and such other objects as may hereinafter appear, my invention relates to the wrist watch strap and the sections thereof as sought to be defined in the appended claims and as described in the accompanying specification taken together with the drawings, in which:

Fig. 1 is a bottom plan view of the wrist watch strap of my present invention, showing the same attached to the wrist watch;

Fig. 2 is a bottom plan view of one of the two sections of the wrist watch strap showing the same in open or unattached condition;

Fig. 3 is a view of Fig. 2 taken in cross-section in the plane of the line 3—3 of Fig. 2;

Fig. 4 is a cross-sectional view of the end of the strap of Fig. 3 showing the same attached to a wrist watch;

Fig. 5 is a perspective view illustrating the first step in attaching the wrist watch strap sections to the watch;

Fig. 6 is a perspective view of the same showing the next step in obtaining the attachment; and

Fig. 7 is a perspective view showing the final step of the attachment and depicting the strap in attached and locked condition on the watch.

Referring now more in detail to the drawings and having reference first to Fig. 1 thereof, the wrist watch strap consists as usual of two sections, namely, a tongue section S and a buckle holding section S'. The tongue section S is provided at one end with a watch attaching portion or loop l and the buckle holding section S' is also provided at one end with a similar watch attaching portion or loop l', and is provided at its other end with a buckle attaching portion 12 in

which are held the buckle 14 and the two usual keepers 16. The tongue section S is provided with a row of perforations 18 for cooperation with the pin of the buckle 14. The watch attaching loops l and l' are removably attachable to

a watch casing W, which latter is provided at the ears 20,20 with the strap attaching bars or bails 22. In the watch here illustrated, the two bars or bails 22,22 are non-removably or fixedly attached to the watch casing W. The watch strap sections S and S' are constructed similarly

in producing or making the watch attaching loops *l* and *l'* thereof; and, thererfore, an explanation of the construction, use and operation of the watch strap section *S* will suffice for a description of both watch strap sections.

In Figs. 2 to 4 of the drawings, I show the construction and the manner of using the tongue strap section *S*. This strap section comprises the top and bottom overlying strap portions *24* and *26*, the top strap portion *24* being longer at one end than and extending from the bottom strap portion *26*, the said extending end *24'* terminating in an anchor shaped piece *28* which is defined by a constricted neck *30* and a winged head *32*. The two strap portions *24* and *26* are stitched together and thus united along their edges by the line of stitching *34*, which, as shown, continues into the extending end section *24'*. The strap section is provided at its underneath face with a plurality of openings through which the anchor shaped piece *28* is threadable for forming the watch attaching loop and for anchoring or locking this loop in attached condition. One opening is preferably the open end *36* of the bottom strap portion *26*, and the other opening comprises a transverse slot *38* formed in and near the end of the said bottom strap portion *26*. The transverse slot *38* has a transverse dimension slightly greater than that of the constricted neck *30* but less than that of the winged head *32* of the anchor shaped tongue *28*. The anchor shaped tongue is foldable after the manner shown in Fig. 4 of the drawings to form the watch attaching loop *l* and is threadable first in and through the opening *36* and then out and through the transverse slot *38* to produce the resulting attached formation shown in Fig. 4 of the drawings. While the transverse dimension of the constricted neck *30* is in the form of the invention depicted in the drawings substantially less than the distance *40* (see Fig. 2) between the longitudinal lines of stitching, in some cases, particularly in very narrow straps especially intended for ladies' use, the lateral or transverse dimension of the constricted neck *30* may be nearly equal to that of the distance *40* between the lines of stitches.

With narrow wrist watch straps or bands as illustrated in the drawings, the problem, becoming even acuter with straps or bands of still narrower width as last referred to, considerable difficulty would be experienced in threading the anchor shaped piece *28* through the watch strap openings, particularly where the wings of the head *32* are sufficiently spread so as to obtain the desired anchoring or locking action. To facilitate the threading operation and the resulting attachment, the head *32* is provided with an aperture *42*. The said aperture *42* is adapted to be engaged by a draw element such, for example, as an ordinary metal clip *44* or a hairpin or bobby pin, after the manner shown in Fig. 5 of the drawings. The complete action is illustrated in Figs. 5, 6 and 7 of the drawings. The clip *44* is engaged by the aperture *42* in the head *32* of the watch strap loop and by means of the clip *44* the anchor shaped tongue section *28* is then drawn through the space behind the bar or bail *22*. Continuing the operation, the clip *44* is then threaded into and through the opening *36* and then through and out of the transverse slot *38* after the manner shown in Fig. 6 of the drawings. Continued drawing of the clip through these openings, of course, results in the drawing of the enlarged head *32* through the openings and particularly the transverse slot *38* in spite

of the relatively narrow lateral dimension of this slot. The final position assumed by the tongue *28* is that shown in Fig. 7 of the drawings. In this position the tongue is locked by the engagement of the opposite wings of the head *32* with the walls of the transverse slot *38*, as most clearly shown in Figs. 1 and 7 of the drawings.

The improved watch strap of my present invention and the manner of making and using the same will in the main be fully apparent from the above-detailed description thereof. The watch strap is devoid of metallic attachments for securing the watch attaching loops in position. The watch strap is made wholly of the material from which the strap is fashioned, such as leather or a plastic. The open tongue *28* may be readily attached to the watch by the user or watch dealer. The tongue is easily threadable as by means of any available metal draw element, such as a clip or a pin, through the watch and then through the watch strap parts. Despite the large transverse size of the head *32*, the tongue is easily and effectively drawn through the relatively narrow transverse locking slot *38* after the manner depicted in Figs. 5 to 7 of the drawings. As soon as the tongue is pulled through the transverse slot, the wings of the head *32* engaging the wall of the slot *38* securely lock the tongue in position. The construction is exceedingly simple. The tongue *28* is a short tongue and is localized effectively at the loop of the strap. The attachment of the loop tongue is wholly underneath the strap and, therefore, not visible to the outside, so that the design of the strap may be made as attractive as is desired.

While I have described my invention in the preferred form, various changes may be made in the described construction without departing from the spirit of the invention defined in the following claims.

I claim:

1. A wrist watch strap section comprising top and bottom overlying strap portions stitched together, the top strap portion being longer at one end than and extending endwise from the bottom strap portion, the said extending end being foldable under to form a watch attaching loop terminating in an anchor shaped piece defined by a constricted neck and a winged head, the said bottom strap portion only being provided adjacent the extension end of the top strap portion with two spaced openings for threadably receiving the said anchor shaped piece, the second of said openings comprising a transverse locking slot whose transverse dimension is less than that of the winged head, the said anchor shaped piece being threadable through said openings and being lockable by engagement of the wings of its head with the wall of the transverse slot.

2. A wrist watch strap section comprising top and bottom overlying strap portions stitched together, the top strap portion being longer at one end than and extending endwise from the bottom strap portion, the said extending end being foldable under to form a watch attaching loop terminating in an anchor shaped piece defined by a constricted neck and a winged head, the said bottom strap portion being open at its end and being provided with a transverse locking slot near its end whose transverse dimension is less than that of the winged head, the said anchor shaped piece being threadable first between the two strap portions at its open end and then through said transverse slot and being lockable

by engagement of the wings of the head with the walls of the transverse slot.

3. A wrist watch strap section comprising top and bottom overlying strap portions stitched together, the top strap portion being longer at one end than and extending endwise from the bottom strap portion, the said extending end being foldable under to form a watch attaching loop terminating in an anchor shaped piece defined by a constricted neck and a winged head, the said winged head being provided with an aperture, the said bottom strap being open at its end and being provided with a transverse locking slot near its end whose transverse dimension is greater than that of the constricted neck but less than that of the winged head, the said anchor shaped piece being threadable first between the two strap portions at its open end and then through said transverse slot by means of a draw element engaged with said aperture, the said anchor shaped

5

piece being lockable by engagement of the wings of said head with the walls of the transverse slot.
